UNITED STATES PATENT OFFICE.

WILLIAM GUÈRIN, OF LIMOGES, FRANCE.

DESIGN FOR A COVERED DISH.

SPECIFICATION forming part of Design No. 22,420, dated May 9, 1893.

Application filed April 5, 1893. Serial No. 469,233. Term of patent 7 years.

To all whom it may concern:

Be it known that I, WILLIAM GUÈRIN, a citizen of France, residing at Limoges, in the Department of Haute-Vienne and Republic 5 of France, have invented and produced a new and original Design for Dishes; and I do hereby declare the following to be a full, clear, and exact description of the same, reference being had to the accompanying drawings, 10 forming a part thereof.

The leading feature of my design consists of a square dish with wavy or irregular configuration, having handles representing shells set on the hinge-end: from the center of each 15 of the four sides of the dish radiate shell-like ornamentation. This same kind of ornamentation passes around the cover near its edge, and likewise around the base of the dish.

Figure 1 represents a plan view of the dish 20 cover, and Fig. 2 a side view of the dish; these two views being deemed necessary to fully illustrate my design.

In Fig. 2, A represents the handle shaped like a half shell with ornamentations at its

base, and shell-like ornamentals radiating 25 on each side B B from the center piece or handle A.

The center C of the body of the dish has a representation of a shell in bas-relief with radiations similar to those on the cover; on 30 each end of the dish are handles shell-like in appearance rising from the undulating sides D D similar to those described on the cover. An irregular shell-like fringe work ornaments the lower parts of the dish and outer 35 edge of the cover E e.

In Fig. 1, a face view of the cover is given with the reverse side of the shell-like handle A and the ornamentals as above described.

What I claim is—

A design for dishes substantially as above described and shown.

In testimony whereof I affix my signature in presence of two witnesses.

W. GUÈRIN.
